UNITED STATES PATENT OFFICE

ERNEST L. SMITH, OF SAN FRANCISCO, CALIFORNIA, ASSIGNOR TO RINGLETTE PERMANENT COMPANY, OF SAN FRANCISCO, CALIFORNIA, A CORPORATION OF CALIFORNIA

APPARATUS FOR USE IN CONNECTION WITH HAIR CURLING AND WAVING DEVICES

Application filed April 2, 1929. Serial No. 352,026.

This invention relates to improvements in hair curling and waving apparatus of that type illustrated in my co-pending application, Serial Number 286,809, filed June 20th, 1928, and application—Hair curling apparatus, filed by me on the 5th day of March, 1929, Serial Number 344,256.

The particular novelty in the present invention resides in the construction of a hand carrying case designed to afford a resistance panel compartment of such design that an inexperienced operator will be enabled to readily determine the correct current flow for the number of curling units in use.

15 A further object is to provide safety devices within the resistance circuit which will automatically operate to protect the customer from shock or injury due to excess temperature; another object is to provide a 20 novel form of case, wherein the instruments and elements employed by the operator may be carried when not in use, making the apparatus self-contained, ready for attachment to a source of electricity at any time the waving units are in position, and the operator 25 is ready to form the curl.

With the above mentioned and other objects in view, the invention consists in the novel construction and combination of parts 30 hereinafter described, illustrated in the accompanying drawings and pointed out in the claim hereto appended; it being understood that various changes in the form, proportion, size and minor details of construction within 35 the scope of the claim may be resorted to without departing from the spirit or sacrificing any of the advantages of the invention.

To more clearly comprehend the invention, reference is directed to the accompanying drawings, wherein:—

40 Figure 1 is a view in side elevation of a plurality of curlers, arranged in operative position on the head, connected in series, with the conductor wires connected at the proper point in the resistance box for the number of curlers employed.

45 Figure 2 is a transverse sectional view on line 2—2, Fig. 1.

50 Referring to the drawings, wherein like characters of reference designate corre-

sponding parts, the numerals 1 and 1' indicate complementary container members substantially oblong in plan, and their upper peripheral edges being inwardly flanged at 2 to afford strength to the respective sections. The container sections are hinged at 3 along corresponding adjacent edges and retaining members 4 on the respective sections cooperate with the sections which swing to closed position to afford retaining means for holding the sections in closed position. A handle 5 serves as a means for transporting the apparatus.

The container section 1' is adapted to be closed by a sliding closure member 6 operating in grooves 7 beneath the flanged edge 2 thereof, and the closure member is adapted for opening and closing movement by reciprocation longitudinally from one end of the container section 1'.

Stop lugs 8 coact with the flange 2 of the opposing container section when the sections are closed to prevent the withdrawal of the cover or closure member 6 from the section 1'.

Within the container section 1 is positioned a flanged frame 9, its lower edge resting on the bottom wall of the container section and its upper flanged edge extending inwardly circumferentially of the container section at 80 a distance below its top edge, as at 10. The side wall of the container section 1 and the side wall of the member 9 are formed with registering vents 11 which permit the heat to pass from the container 1, and the upper flanged wall 10 is also vented at 12.

Closing the apertures in the frame 9 is a panel board 13 of bakelite or other insulating material, it being held in position by screws or other fastening devices 14.

Disposed transversely of the container section 1, beneath the panel board 13, are insulating supporting cores 15 having wound thereon resistances 16, the resistances being arranged in series, as indicated in Fig. 1. The series of resistances are provided at points between adjacent resistances with tap switches 17 accessible through apertures 18 in the panel board 13, the apertures being consecutively numbered from one end of the series 95 100

toward the other, and at the end of the series of resistances is located a fuse 19 and a lamp 20.

When in use, the operator affixes the number of curling units desired onto the head of the customer, the units being of the type set forth and described in my application filed on the 5th day of March, 1929 and entitled—Hair curling apparatus; connects the units in series, as at A, and from one end of the series plugs a lead-in B into the tap switch marked corresponding to the number of units employed. The other end of the series of units (lead C) connects with a source of current, as does the lead D, which taps into tap switch 21 at the end of the series of resistances. The capacity of the resistances between leads B and D is sufficient to reduce the current flow through the curling device to insure heating to the proper temperature, it being understood that the greater the number of curling units employed the lesser number of resistances are included between leads B and D.

25 The container section 1' affords a receptacle for the curling units and accessories employed in the treatment of the hair, and the parts are precluded from accidentally falling out of the section by the cover 6, the latter also precluding contact between the accessories and the face of the panel board 13.

I claim:—

In a hair curling and waving device having a plurality of curler members connected in series and each provided with a heating element and removable contacts for intake and outlet of electric current, a rheostat comprising a plurality of resistance units having substantially similar capacity and mounted in spaced parallel relation and connected in series at their ends by an electrical conduit, a tap switch in each of said conduits intermediate ends of resistance units connected thereby, a non-conducting plate overlying said resistance units provided with openings in communication with each of said tap switches, and adapted to receive therein a contact member, and an electric circuit adapted to connect one end of said series of curlers to a source of electrical energy, and the other end of said series of curlers to a source of electrical energy through said resistances.

In testimony whereof I have signed my name to this specification.

ERNEST L. SMITH.
